UNITED STATES PATENT OFFICE.

WILLIAM TH. REED, OF WINNIPEG, MANITOBA, ASSIGNOR OF ONE-HALF
TO PETER CLARKE, OF TORONTO, CANADA.

SPARK-ARRESTER.

SPECIFICATION forming part of Letters Patent No. 364,857, dated June 14, 1887.

Application filed February 23, 1887. Serial No. 229,073. (No model.)

To all whom it may concern:

Be it known that I, WILLIAM THOMAS REED, of the city of Winnipeg, in the county of Selkirk, in the Province of Manitoba, Canada, 5 mechanical engineer, have invented certain new and useful Improvements in Spark-Arresters, of which the following is a specification.

The principal object of the invention is to 10 design a spark-arrester which will enable the use of a large exhaust-nozzle and will equalize the draft in the smoke-box of the locomotive, and is designed more especially as an improvement 15 on the device patented to me November 9, 1886, No. 352,353; and it consists, essentially, in forming a central air-tube in the exhaust-pipe communicating with the interior of the smoke-box at a point near the bottom of the smoke-box, and extending thence to the 20 mouth of the exhaust-nozzle, corrugated deflecting-plates being arranged in the smoke box and stack, substantially in the manner hereinafter more particularly explained.

Figure 1 is a perspective sectional view of 25 a smoke box and stack with my device applied. Fig. 2 is a sectional side view of the exhaust-pipe. Fig. 3 is a sectional rear view of the exhaust pipe.

A represents the exhaust-pipe, communicating 30 in the usual manner with the cylinders of the engine.

a is a central tube extending from a point near the bottom of the smoke-box B to the mouth of the exhaust-nozzle b.

35 In the drawings I show the lower mouth of the tube a facing the front of the smoke-box; but I do not confine myself to that exact position, as any point near the bottom of the smoke-box will answer my purpose.

40 C is a petticoat extending over the lower mouth of the tube a. The bottom of this petticoat C is preferably covered with wire-netting h in order to prevent large cinders entering the central tube, a.

45 The smoke-stack D is of the ordinary class known as "straight" smoke-stacks; but I corrugate its bonnet at d, as indicated, and suspend in its center a corrugated cone, E, substantially in the manner indicated.

50 F is a corrugated deflecting-plate situated in front of the tubes G, as shown.

H is a corrugated base-plate, and I is a corrugated plate placed on the front of the smoke-box.

J is a wire-netting extending across the 55 smoke-box B just below the mouth of the nozzle b.

By forming a central tube, a, in the exhaust-pipe A, the exhaust-steam in escaping through the nozzle b will naturally produce a partial 60 vacuum in the central tube, a. Consequently a draft is produced near the bottom of the smoke-box B, as well as near its top, thereby equalizing or distributing the draft equally over the surface of the tubes; and as a consequence I am able to use a much larger nozzle b than would be possible were the draft to be produced only at the top of the smoke-box. 65

Owing to the form of my exhaust-nozzle b, the steam discharged from it will ascend the 70 smoke-stack in the form of a hollow column, the center of which will contain a core of the cinders which may be drawn into the central tube, a. These cinders will strike the corrugated cone E, and, flying off at a tangent from 75 it, will come in contact with the corrugations d, and in this way will be effectually ground to a powder before they can escape from the stack.

Owing to the arrangement of the corrugated 80 plates F, H, and I, the cinders entering the smoke-box B from the tubes G will be ground pretty finely before they can escape through the netting J or through the central tube, a. Consequently the corrugated cone E and corrugations d will not have a great deal of work 85 to accomplish.

What I claim as my invention is—

1. An exhaust-pipe having a central tube extending from a point near the bottom of the 90 smoke-box to a point at or near the mouth of the exhaust-nozzle, substantially as and for the purpose specified.

2. An exhaust-pipe having a central tube extending from a point near the bottom of the 95 smoke-box to a point at or near the mouth of the exhaust-nozzle, in combination with a petticoat extending over the lower mouth of the said tube, substantially as and for the purpose specified.

3. An exhaust-pipe having a central tube extending from a point near the bottom of the 100

smoke-box to a point at or near the mouth of the exhaust-nozzle, in combination with a petticoat extending over the lower mouth of the said tube, and a netting extending over the bottom of the petticoat, substantially as and for the purpose specified.

4. A straight smoke-stack, D, having a corrugated cone, E, suspended from its top, and corrugations *d* formed within it on the under side of the bonnet around said cone, substantially as and for the purpose specified.

5. The corrugated deflecting-plate F, the corrugated base-plate H, and corrugated front plate, I, arranged, as specified, in the smoke-box B, below the wire-netting J, in combination with an exhaust-pipe, A, having a central tube, *a*, extending from a point near the bot-

tom of the smoke-box B to a point at or near the top of the exhaust-nozzle *b*, substantially as and for the purpose specified.

6. The exhaust-pipe A, having a central tube, *a*, extending from a point near the bottom of the smoke-box B to a point at or near the mouth of the exhaust-nozzle *b*, in combination with the corrugated cone E, suspended in the center of the smoke-stack D, having corrugations *d* formed in it, substantially as and for the purpose specified.

Toronto, January 31, 1887.

W. TH. REED.
